UNITED STATES PATENT OFFICE

GEORGE H. STEPHENS, OF NORTHBROOK, ILLINOIS, ASSIGNOR TO THE HAMMOND CLOCK COMPANY, OF CHICAGO, ILLINOIS, A CORPORATION OF DELAWARE

DESIGN FOR A CLOCK CASE OR SIMILAR ARTICLE

Application filed March 14, 1931. Serial No. 39,092. Term of patent 14 years.

To all whom it may concern:

Be it known that I, GEORGE H. STEPHENS, a citizen of the United States, residing at Northbrook, in the county of Cook and State of Illinois, have invented a new, original, and ornamental Design for a Clock Case or Similar Article, of which the following is a specification, reference being had to the accompanying drawing, forming a part thereof.

The figure is a front perspective view of a clock case or similar article showing my new design.

I claim:

The ornamental design for a clock case or similar article, as shown.

In witness whereof, I hereunto subscribe my name this third day of March, 1931.

GEORGE H. STEPHENS.
